(57) **CLAIM**
The ornamental design for a case for a printer, as shown and described.

DESCRIPTION

FIG. 1 is a top front perspective view of a case for a printer showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof; and,
FIG. 8 is a top front exploded perspective view thereof showing portions of the case in alternate positions.

The broken lines illustrating portions of the case for a printer are for environmental purposes only and form no part of the claimed design.

1 Claim, 5 Drawing Sheets**FIG. 1**

FIG. 2**FIG. 3**

FIG. 4

FIG. 5

FIG. 6**FIG. 7**

FIG. 8
